BY *Munn & Co.*

ATTORNEYS

UNITED STATES PATENT OFFICE.

BENJAMIN T. CARSON, OF RENSSELAER, NEW YORK.

TOOL-HOLDER.

1,392,269.

Specification of Letters Patent. Patented Sept. 27, 1921.

Application filed March 22, 1921. Serial No. 454,366.

To all whom it may concern:

Be it known that I, BENJAMIN T. CARSON, a citizen of the United States, and resident of Rensselaer, in the county of Rensselaer and State of New York, have invented a new and Improved Tool-Holder, of which the following is a full, clear, and exact description.

This invention relates to lathe tools and more particularly to a tool holder, the same being an improvement over my co-pending application filed March 9th, 1920, and bearing Serial No. 364406 patented June 21, 1921, No. 1,382,413. In the present invention the shank of the tool holder and the yoke which co-acts therewith are of identical construction and function exactly as in my prior application. The improvement consists of an attachment therefor in the nature of a locking or retaining device which seeks for its object to provide a positive means for clamping the yoke in its adjusted positions and locking the tool against relative movement with respect to the holder.

Another object in view is to provide an attachment of the character described which does not materially add to the expense of manufacture of the tool and which is extremely simple to manipulate.

With the above recited and other objects in view, some of which will appear more clearly hereafter, the invention resides in the novel construction, combination and arrangement of parts set forth in the following specification, pointed out in the appended claims and illustrated in the accompanying drawings, in which—

Figure 1 is a side elevation of the tool holder equipped with the improved attachment and illustrating a tool arranged in position therein.

Fig. 2 is a plan view thereof with the attachment removed.

Fig. 3 is an end view with the attachment applied.

Fig. 4 is a fragmentary plan view of the shank with the yoke and attachment removed.

Fig. 5 is a fragmentary side elevation thereof.

Fig. 6 is a plan view of the yoke removed from the shank.

Fig. 7 is a sectional view taken approximately on the line 7—7 of Fig. 6.

Fig. 8 is a plan view of the clamp element

of the attachment removed from the tool holder.

Fig. 9 is a sectional view therethrough taken approximately on the line 9—9 of Fig. 8.

Referring to the drawings by characters of reference which denote like parts throughout several views thereof, 10 designates a tool which is here illustrated as the "diamond point" type and 11 the shank of the tool holder which is preferably of rectangular formation in cross section and is provided at one extremity with a head 12 which is preferably formed integral therewith. The outer end wall 13 is inclined and provided with a vertically arranged V-shaped groove 14. The rear edges 15 of the head which are preferably formed by the vertical grooves 16 cut in the opposite side faces of the shank are disposed at an angle to the inclined outer end wall 13 of the head. The juncture of the head with the body portion of the shank provides shoulders 17 which are preferably beveled slightly toward the outer end wall. The yoke 18 which is adapted to be associated with the head of the shank for securing the tool 10 in place and clamping the same against the end wall is preferably of U-shaped formation and comprises side arms 19 and a connecting portion or bight 20, the inner face of which is grooved as at 21. As illustrated the free extremities of the legs 19 are each provided with an inwardly extending flange 22 constituting a shoulder which is disposed at an angle with respect to the bight 20. The angularity of the flanges 22 are substantially identical to that of the shoulders 17 formed on the shank head and the inclination of the bight 20 conforms to and is substantially identical with the inclination of the end wall 13.

In use of the tool holder, the yoke is applied to the head of the shank with the legs 19 straddling the same and the inner edges of the flanges 22 in engagement with the shoulders 17. It will be understood that upon vertical sliding movement of the yoke the bight 20 will be moved toward or away from the end wall 13 to increase or decrease the size of the socket formed by the end wall 13 and the bight. The configuration of the grooves 21 and 14 may be varied to conform to the shape of the tool which it is desired to receive. By reference to Fig. 1 of the drawing it will be seen that as the

110

yoke is moved downwardly, the co-acting engagement of the shoulders 17 and the flanges 22 will serve to effect relative movement of the bight of the yoke toward the 5 end wall 13 whereby to clamp the tool against said end wall. A reverse movement of the yoke will move the bight 20 away from the end wall to permit of the removal of the tool. Likewise the movement of the 10 yoke and the resulting relative movement of the bight toward or away from the end wall will serve to increase or decrease the socket which is formed by the end wall and the bight to accommodate tools of varying cross 15 sectional dimensions.

The attachment consists of a clamping member 23 preferably constructed from a steel plate of a width substantially equal to the width of the yoke and conforming to the 20 shape of the inner end of the same. The outer end thereof is provided with a V-shaped notch 24 which conforms to the shape of the groove 14 in the outer end of the shank head. The rear end 25 of the 25 clamp member is disposed at an angle to the major portion of the same to conform to the shape of the rear end of the yoke. The clamp member is centrally apertured as at 26 to receive therethrough the shank of a retaining screw 27, the threaded portion 28 30 of which engages in the threaded socket 29 formed in the shank head 12.

After the tool 10 has been arranged and clamped by the yoke to the end of the 35 shank, the clamp member 23 is positioned on the yoke and the retaining screw 27 is inserted through the central aperture 26 thereof and engaged in the folded socket 29 to lock and retain the yoke in relatively 40 adjusted position with respect to the shank head thereby positively eliminating any possibility of slipping which would tend to loosen the tool. The screw 27 may be also employed to advance and jam the co-acting 45 shoulders and flanges 17 and 22 of the shank head and yoke.

It is to be understood that the right is reserved to embodiments other than those 50 actually illustrated herein, to the full extent indicated by the general meaning of the terms in which the claims are expressed and by variations in the phraseology of the same.

I claim:

55 1. The combination with a tool holder including a shank, an angular outer end provided with a vertical groove, a yoke member adapted to be supported from said end of the shank to constitute a tool receiving 60 socket and means formed respectively on the yoke and the side faces of said shank end adapted to co-act upon relative vertical adjustments to vary the size of the tool receiving socket, of means for positively locking the yoke to the shank.

2. The combination with a tool holder including a shank, an angular outer end provided with a vertical groove, a yoke member adapted to be supported from said end of the shank to constitute a tool receiving 70 socket and means formed respectively on the yoke and the side faces of said shank end adapted to co-act upon relative vertical adjustments to vary the size of the tool receiving socket, of means for positively locking the yoke to the shank, said means comprising an internally threaded apertured portion in the shank head, an apertured plate bridging the yoke member and a headed screw having a threaded shank adapted 75 to be inserted through the apertured plate and engaged in the threaded apertured portion of the head.

20 3. In a tool holder, a shank and means for clamping a tool to one end thereof, comprising wedge-shaped portions formed on opposite sides of the shank adjacent one end thereof, a yoke having wedge-shaped portions adapted to co-act with the wedge-shaped portions on the shank whereby upon 90 vertical adjustments of the yoke the bight of the same will be advanced toward or away from the end of the shank, and means carried by the yoke and adapted to co-act with the shank to lock and retain the yoke 95 in its adjusted positions thereon.

4. A tool holder comprising a shank having portions formed on the opposite sides thereof disposed at an angle to its terminal, a member having a bight and side legs 100 adapted to straddle the shank, opposed portions on the inner side of the legs disposed at an angle to the bight and adapted to co-act with the portions of the shank to effect relative movement of the bight and shank upon vertical adjustments of the member, an apertured plate adapted to bridge the upper and inner ends of the legs, an internally threaded apertured portion in the upper end of the shank disposed in alignment with the aperture of said plate and a screw having a threaded shank inserted through said aligned apertures and co-acting with the internally threaded apertured portion of the shank to provide means for locking the bight in its relatively adjusted 110 relations to the shank.

5. The combination with a tool holder comprising a shank, a tool seat at the forward end of the shank, a clamping device 120 having means to engage the tool opposite the tool seat, and a complementary sliding connection between the shank and clamping device, said sliding connection inclined with relation to the tool seat, of means for positively locking the clamping device to the shank.

6. The combination with a tool holder, including a shank, a tool seat at the forward end of the shank, a clamping device, 130

complementary engaging shoulders between the yoke and shank, said shoulders being relatively inclined to the tool seat, of means for positively locking the yoke to the shank.

5 7. The combination with a tool holder, including a shank, a tool seat at the forward end of the shank, a clamping yoke, complementary engaging shoulders between the yoke and shank, said shoulders being

10 relatively inclined to the tool seat, of means

for positively locking the yoke to the shank, said means comprising an internally threaded apertured portion in the shank, an apertured plate bridging the yoke member, and a headed screw having a threaded shank inserable through the apertured plate and engaged within the threaded apertured portion of the shank. 15

BENJAMIN T. CARSON.
